US00D441091S

(12) **United States Design Patent**
Day

(10) Patent No.: **US D441,091 S**
(45) Date of Patent: ** Apr. 24, 2001

(54) **PCR PLATE**

(75) Inventor: **Paul Day**, Chipstead (GB)

(73) Assignee: **Advanced Biotechnologies Limited**
(GB)

(**) Term: **14 Years**

(21) Appl. No.: **29/112,690**

(22) Filed: **Oct. 21, 1999**

(30) **Foreign Application Priority Data**

Apr. 24, 1999 (GB) 2082919

(51) LOC (7) Cl. **24-02**

(52) U.S. Cl. **D24/224; D24/226; D24/230**

(57) **CLAIM**

I claim the ornamental design for a PCR plate, as shown and described.

DESCRIPTION

FIG. 1 is a top view of the PCR plate of the present invention:

FIG. 2 is a bottom view of the PCR plate of FIG. 1;

FIG. 3 is a front elevational view of the PCR plate of FIG. 1;

FIG. 4 is a rear elevational view of the PCR plate of FIG. 1;

FIG. 5 is a left side elevational view of the PCR plate of FIG. 1; and,

FIG. 6 is a right side elevational view of the PCR plate of FIG. 1.

1 Claim, 2 Drawing Sheets

FIG. 1

FIG. 2
